UNITED STATES PATENT OFFICE

CHARLES B. JOHNSON, OF PATERSON, NEW JERSEY

WARP-SIZING MACHINE

Application filed May 11, 1929. Serial No. 362,338.

Warp sizing machines are known in which, with apparatus to apply size to and dry the size on the warp including a rotary system to advance the warp at constant rate while the warp is being wound up on a beam or other rotary core, there is slip-friction rotation-transmitting means connecting said system and the core, whereby the application and drying of the size will be uniform and the mass of windings will be compactly wound. (See my Patent No. 1,540,265.)

One object of the present invention is to provide in a machine of the mentioned type for the treatment of a number of independent sections of warp, as the warps for as many different ribbons or other narrow-ware goods, simultaneously. In respect to this object the invention consists in combining, with a supporting structure and apparatus as aforesaid but common to all the sections and with rotary cores on which to wind the sections, several slip-friction rotation-transmitting means respectively connecting said cores with the said system of said apparatus.

A further object is, given the said apparatus, to provide for the traverse of a core lengthwise of its axis while the winding is progressing, whereby the winding will be spirally effected. In respect to this object the invention consists in combining, with a supporting frame and apparatus to apply size to and dry the size on the warp, a carriage traversable in said frame transversely of the advance of the warp, a rotary core onto which to wind the warp revolvably supported in and traversable with the carriage and rotation transmitting means connecting said core with said system of said apparatus.

A further object is, given the said apparatus so characterized, to provide for shiftability of a warp-package core to different positions transversely of the advance of the warp. In respect to this the invention consists in combining, with a supporting structure and said apparatus, the same including in its rotary system a rotary splined shaft, a support for the warp shiftable on said structure lengthwise of the shaft, and rotation-transmitting means shiftable with said support and connecting the core with said shaft.

Other objects, having in view to increase the general efficiency of the machine, will be hereinafter pointed out.

In the drawings,

Fig. 1 is a side elevation of a warp sizing machine embodying the present invention;

Figs. 2 and 3 are a plan and side elevation, respectively, of the left-hand end thereof; and

Figs. 4 and 5 are sections on lines 4—4 and 5—5, Fig. 2, and Figs. 6 and 7 are sections on lines 6—6 and 7—7, Figs. 4 and 5, respectively.

The sections A of warp, wound on a beam 1 journaled in the right-hand end of the machine in Fig. 1, extend between the liquid-size-applying rollers 2a of a "quetch" 2 and then successively around the heated drums 3, thus first receiving the size and having it dried thereon. The drums feed the sections 70 through the machine and are positively driven from a motor 4 through gearing 5—6—7—8—9, the gear 9 meshing with one of the three gears 10 on the drums which are further geared to rotate together by the gearing 11, (see Figs. 1 and 2). The rollers of the quetch are driven in the appropriate direction by the belt-and-pulley drive from one of the drum gears 10. The mechanism thus far described is known.

The frame 13, supporting said mechanism, has two rigid arms 14 projecting to the left (Figs. 1 and 2) and thereon is slideable transversely of the travel of the warp sections a carriage 15 comprising three parallel bars 15a rigidly connected at their ends by the cross-heads 15b; the carriage runs on rollers 16 and is guided by rollers 17 having flanges overlapping the bars 15a, said rollers being journaled in the arms. The carriage is reciprocated through a lever 18 having a roller 18a engaged with a cam 19 on a shaft 20 journaled in the frame and geared with the shaft 8a common to gears 8 and 9 by the gearing 21—22—23—24—25—26, the last gear (26) of this train being shiftable into and out of mesh with the gear 25 (thus in effect forming a clutch) by the handle 27 thus either to establish or arrest the traverse motion of the carriage, according as the 100

winding of the warp-sections is to be with or without traverse. The connection between the lever and carriage is afforded by a roller 28a on a nut 28 and engaged with a slot 18b in the lever, the nut being engaged with a hand-screw 29 journaled in the carriage.

In the carriage, parallel with and between the bars 15a, are journaled the splined shafts 30 confined to traverse therewith by collars 30a and rotated as follows (Figs. 4 and 6): In ball-bearings of brackets 14a on one of the arms 14 are journaled sleeves 31 having beveled roller-splines 32 engaged in the opposite spline-ways or grooves of the shafts 30 and also having sprocket-wheels 33. Below one such sleeve a short shaft 34 is journaled in the arm 14, having a sprocket-wheel 35 at one end and a pulley 36 at the other. The sprocket-wheels 33 and 36 are connected by an endless chain 37, 38 being its tightening means. The pulley 36 is connected with the pulley 39 on the shaft of the gears 6-7 by a belt 40. Thus the shafts 30 are constantly rotated, the roller-splines practically eliminating the resistance and wear otherwise present when the carriage and hence said shafts are undergoing traverse.

The carriage includes alternately arranged head-stocks and tail-stocks having live and dead spindles and thus forming supports for the cores, the same being individually adjustable lengthwise of and also removable from the carriage bars 15a and the head-stocks containing gearing through which the live spindles are individually driven by friction variable at the will of the operator as the several wound packages increase in diameter, thus (Figs. 5 and 7):

41 is a head-stock formed as a hollow housing and seated on two of the bars 15a to one of which it is secured by clamping means 42 so that it may be set and secured in any position along the bars or removed therefrom. It is penetrated by the intervening shaft 30 and to permit its removal the portion thereof below this shaft is a separate part hinged at 43 and held in its normal relation to the remainder of the housing by the clamping means 44; when the latter is released the hinged part may swing down to clear the shaft. In the head-stock is journaled the live-spindle 45 confined against endwise movement by a face-plate 45a exterior of and a pinion 45b within the head-stock. On the shaft 30 within the head-stock and shiftable therewith along said shaft is splined a pinion 46. This pinion and the live-spindle pinion are connected by gears 47 and 48 respectively meshing therewith and journaled on a common axis face to face, one having a friction-grip means 49 engaging the other. These two pinions are penetrated by a shaft 50 fixed in the head-stock and having a nut 51 screwed thereon and between the nut and pinion 48 a spring 52, whereby the frictional

resistance of the means 49 may be manually varied. 53 denotes the corresponding tail-stock clamped to said two bars by means 54 (Fig. 3) similar to 42 and 55 the dead-spindle secured therein by the set-screw 56 and having any suitable freely revoluble means 57 to receive one end of the core B which is pinned or otherwise fixed to rotate with the live-spindle 45 at 58. The head-stock is clamped not only to one bar by manipulating the means 42 but to the other by manipulating the means 44 (see Fig. 5). The construction is such, moreover, that not only is the head-stock and its contained parts (except 30 and 46) removable as a unit but by affording a bearing for the pinion 46 the head-stock prevents shaft 30 from springing as a result of possible binding of pinions 46-47 on each other (see Fig. 7).

A pair of overhanging supports 59 are secured on arms 14 and in these are revoluble adjustable shafts 60 carrying in cranks the guide-bars 60a and having hand-wheels 60b. In the illustrated instance there are two parallel sets of wound packages being formed and the two guide-bars guide the warp sections in two sets to the respective sets of wound masses. By its hand-wheel each guide-bar may be adjusted as required.

Given supporting structure and apparatus therein to apply size to and dry the size on the sections being treated including a drying drum revolving at constant rate and a power distributing shaft (as 30) arranged parallel and also connected to rotate with the drum, we have in the foregoing rotary cores on which to wind the respective sections operatively supported in said structure, and separate slip-friction rotation-transmitting means connecting the respective cores with the shaft. As herein set forth, said structure comprises a frame in which the drum is journaled and a carriage traversable in the frame lengthwise of the shaft and in which the cores are operatively supported and with which said slip-friction rotation-transmitting means is traversable. More specifically, in the example the shaft is actually journaled in said carriage. Still more specifically, in the example there are separate means for supporting the cores on the carriage and these are adjustable thereon independently lengthwise of and with respect to the shaft so journaled therein. It will be understood that the slip-friction of said rotation-transmitting means allows for the tendency of each package being formed to rotate at greater surface speed than the drums, whereby to keep the sections taut, and for the increase in diameter of each package.

It will be understood that in certain aspects the supporting structure may be taken as including the carriage with the frame.

Having thus fully described my invention, what I claim is:

1. In combination, a frame, a rotary driving member journaled therein, a carriage traversable lengthwise of the axis of said member, winding means including a warp-package core and journaled in and traversing with the carriage and means to transmit rotation to the core from said member including a shaft revolvable in and traversing with the carriage and extending axially through and splined in said member.

2. In combination, a frame, a rotary driving member journaled therein, a carriage traversable lengthwise of the axis of said member, winding means including a warp-package core and journaled in and traversing with the carriage and means to transmit rotation to the core from said member including a shaft revolvable in and traversing with the carriage and extending axially through and splined in said member, said carriage having a support for the core adjustable relatively to the remainder of the carriage lengthwise of the axis of said member.

3. Winding mechanism comprising, in combination, a supporting structure, a driving shaft journaled therein, a head-stock arranged on said structure and penetrated by the shaft and comprising sections separable to permit the removal of the head-stock from the shaft, a live spindle journaled in one such section and gearing connecting said spindle and shaft and also journaled in said section.

4. Winding mechanism comprising, in combination, a supporting structure, a driving shaft journaled therein, a sectional head-stock penetrated by the shaft and having its sections separable to permit removal of the head-stock from the shaft, rotary means in the head-stock intergeared with the shaft to be rotated thereby, and means to clamp said sections together and to said structure, said head-stock when so clamped confining the shaft from springing.

5. In combination, with a supporting structure and apparatus therein to apply size to and dry the size on the sections being treated including a drying drum revolving at constant rate and a power distributing shaft arranged parallel and also connected to rotate with the drum, of rotary cores on which to wind the respective sections operatively supported in said structure in offset relation to each other lengthwise of the shaft, and separate slip-friction rotation-transmitting means connecting the respective cores with the shaft.

6. In combination, with a supporting structure and apparatus therein to apply size to and dry the size on the sections being treated including a drying drum revolving at constant rate and a power distributing shaft arranged parallel and also connected to rotate with the drum, said structure compris-

ing a frame in which the drum is journaled and a carriage traversable in the frame lengthwise of the shaft, of rotary cores on which to wind the respective sections operatively supported in the carriage, and separate slip-friction rotation-transmitting means connecting the respective cores with the shaft and traversable with the carriage.

7. In combination, with a supporting structure and apparatus therein to apply size to and dry the size on the sections being treated including a drying drum revolving at constant rate and a power distributing shaft arranged parallel and also connected to rotate with the drum, said structure comprising a frame in which the drum is journaled and a carriage traversable in the frame lengthwise of the shaft and having the latter journaled therein and traversable therewith, of rotary cores on which to wind the respective sections operatively supported in the carriage, and separate slip-friction rotation-transmitting means connecting the respective cores with the shaft and traversable with the carriage.

8. In combination, with a supporting structure and apparatus therein to apply size to and dry the size on the sections being treated including a drying drum revolving at constant rate and a power distributing shaft arranged parallel and also connected to rotate with the drum, said structure comprising a frame in which the drum is journaled and a carriage traversable in the frame lengthwise of the shaft and having the latter journaled therein and traversable therewith, of rotary cores on which to wind the respective sections, separate means for supporting the cores independently adjustable on the carriage lengthwise of and with respect to the shaft, and separate slip-friction rotation-transmitting means connecting the respective cores with the shaft and traversable with the carriage.

In testimony whereof I affix my signature.

CHARLES B. JOHNSON.
